DESIGN FOR A BODY FOR STRINGED MUSICAL INSTRUMENTS

Anthony G. Cox, Honolulu, Territory of
Hawaii

Application November 28, 1938, Serial No. 81,438

Term of patent 14 years

To all whom it may concern:

Be it known that I, Anthony G. Cox, a citizen of the United States, residing at Honolulu, in the county of Honolulu and Territory of Hawaii, have invented a new, original, and ornamental Design for a Body for Stringed Musical Instruments, of which the following is a specification, reference being had to the accompanying drawing, forming part thereof, in which:

Figure 1 is a top plan view of the body for stringed musical instruments showing my new design.

Figure 2 is a side elevational view of the same.
Figure 3 is a bottom plan view.

I claim:

The ornamental design for a body for stringed musical instruments, as shown.

ANTHONY G. COX.
